(57) **CLAIM**

The ornamental design for a beverage stein, as shown and
described.

DESCRIPTION

FIG. 1 is a top, front, perspective view of a beverage stein
showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, perspective view of the beverage stein
showing a second embodiment of our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The features shown in broken lines are portions of the
beverage stein or environmental subject matter to the beverage
stein forming no part of the claimed design. The features
shown in long dash-short dash bolded broken lines indicate
the bounds of the claimed design and otherwise form no part
of the claimed design.

1 Claim, 14 Drawing Sheets
